UNITED STATES PATENT OFFICE.

HARDIN E. SOLBRIG, OF DEXTER, INDIANA.

SPARK-PLUG CLEANER.

1,117,102.

Specification of Letters Patent. Patented Nov. 10, 1914.

Application filed May 5, 1914. Serial No. 996,458.

To all whom it may concern:

Be it known that I, HARDIN E. SOLBRIG, a citizen of the United States, residing at Dexter, in the county of Perry and State of Indiana, have invented certain new and useful Improvements in Spark-Plug Cleaners, of which the following is a specification.

This invention has relation to spark plugs for internal combustion engines and more particularly to devices specially designed for cleaning the points of the plug and preventing the collection of carbon and other non-conducting material thereon.

An object of the invention is the provision of a device of this character having connection with a driven part of the engine whereby the cleaner is actuated subsequently to each explosion to clean the deposit of carbon resulting from the explosion.

With these and other objects in view, the invention consists in the novel construction, arrangement and combination of parts as will be hereinafter specifically described, claimed and illustrated in the accompanying drawings, in which,

Figure 1 represents a fragmental sectional view through the cylinder of the internal combustion engine, showing the application of my invention thereto, and, Fig. 2 represents a transverse sectional view of the cleaner brush.

Referring to the drawing in detail, wherein similar reference numerals designate corresponding parts throughout the several views, the numeral 1 indicates the head of the cylinder of the internal combustion engine having an intake or exhaust port 2 therein adapted to be intermittently closed by a valve 3 carrying a stem 4 adapted to be operated by one end of the rocker arm 5 pivoted at 6 in the supporting bracket 7 and connected at its opposite end with the valve rod 8. The port 2 in the cylinder communicates with the pipe 9 for conducting the products of combustion from the cylinder or feeding the liquid fuel thereto. Adjacent the intake port 2 a threaded opening 10 is formed in the cylinder 1 receiving a plug 11 having an angular head 12 carrying the supporting bracket 7. If desired, the bracket 7 may be formed integral with or secured directly to the cylinder 1.

The plug 11 is formed with a threaded aperture 12 receiving the body of a spark plug 13 having spaced points 14 providing a spark gap 15 therebetween. As clearly

illustrated in Fig. 1, the points 14 are directed laterally of the body of the plug whereby they may be cleaned by the brush hereinafter described. The opening 12 in the plug is formed eccentrically therein, and a second opening 16 is formed therethrough having a threaded boss 17 at one end carrying a packing nut 18.

A cylindrical shank 19 of the brush is slidably positioned through the opening 16 and through the cap or nut 18 and is pivotally mounted by a pin 20 in the slot 21 formed in the rocker arm 5 intermediate the pivotal axis 6 thereof and the valve actuating end.

The shank 19 extends into the cylinder 1 and is formed with a pair of parallel spaced flanges 22 directed toward the plug 13 and providing a housing for a plurality of wires 23 also directed toward the plug 13.

In operation, the rocker arm 5 is actuated by the valve rod 8 having connection with the engine shaft or other part thereof seating and unseating the valve 3 as the piston reciprocates within the cylinder 1. Obviously, the valve 3 is opened subsequently to the explosion within the cylinder 1 and as the latter is taking gas. The inward movement of one end of the rocker arm 5 causing the opening of the valve 3, moves the shank 19 of the brush inwardly brushing the wires across the points 14, thus effectively cleaning the latter. As the cylinder is primed for the next explosion, the valve 3 is closed by the rocker arm 5, the latter throwing the shank 19 outwardly and moving the brush to its normal full line position.

What I claim is:

1. A device of the character described comprising the combination with a cylinder, a valve therefor, valve operating means, and a spark plug; of a cleaner member connected with said operating means extending within said cylinder and adapted to clean the points of said spark plug. 95

2. A device of the character described comprising the combination with a cylinder, a valve therein, operating means for the valve, and a spark plug; of a shank connected with said operating means, and cleaner means carried by the inner end of said shank adapted to be reciprocated across the points of said spark plug. 105

3. The combination with a cylinder, a valve therein, operating means for the valve,

spark plug, a shank slideable through said cylinder and having pivotal connection with said valve operating means, spark plug cleaning means carried by the inner end of said shank, and flanges on said shank engaging said cleaning means.

4. The combination with a cylinder, a valve operable in said cylinder, operating means for said valve, a plug removably secured in said cylinder, a spark plug removably secured in said plug, of a shank slideable in said plug and having pivotal con-

nection at its outer end with said valve operating means, and a brush on the inner end of said shank adapted to be reciprocated across the points of said spark plug to clean the latter.

In testimony whereof I affix my signature in presence of two witnesses.

HARDIN E. SOLBRIG.
